ADOLPH M. HOLSTEIN, OF SYRACUSE, NEW YORK.

DESIGN FOR FURNITURE, CASKET, INTERIOR OR EXTERIOR DECORATION.

52,794.

Specification for Design.

Patented Dec. 24, 1918.

Application filed August 22, 1917. Serial No. 187,543. Term of patent 3½ years.

To all whom it may concern:

Be it known that I, ADOLPH M. HOLSTEIN, a citizen of the United States, residing at Syracuse, in the county of Onondaga and State of New York, have invented a new and original and ornamental Design for Furniture, Casket, Interior or Exterior Decoration, of which the following is a specification, reference being had to the accompanying drawing, forming a part hereof, which is a face view of the decoration.

The drawing is an elevation or face view of this design.

This design consists of a horizontally elongated rectangular arrangement of bamboo like rods, and posts, the latter being spaced

at regular intervals along the horizontal rods, and inclined bamboo like rods meeting the lowermost horizontal rod at its ends and intersecting each other above the middle portion of the upper most horizontal rod, the rods being entwined with twigs, leaves and flowers to create an oriental atmosphere.

I claim:

An ornamental design for furniture, casket, interior or exterior decoration, substantially as shown and described.

In testimony whereof, I have hereunto signed my name, at Syracuse, in the county of Onondaga, and State of New York, this 29th day of June, 1917.

ADOLPH M. HOLSTEIN.
